Fig. 3

The base of my design is essentially plain and unornamented.

I claim:

The ornamented design for an outdoor drinking fountain, as shown and described.
